(57) **CLAIM**

The ornamental design for headset for helmet as shown and described.

DESCRIPTION

FIG. 1 is a front perspective view of a headset for helmet according to the present invention.

FIG. 2 is a rear perspective view of the headset for helmet illustrated in FIG. 1.

FIG. 3 is another front perspective view of the headset for helmet illustrated in FIG. 1.

FIG. 4 is another rear perspective view of the headset for helmet illustrated in FIG. 1.

FIG. 5 is a side elevation view of the headset for helmet illustrated in FIG. 1.

FIG. 6 is another side elevation view of the headset for helmet illustrated in FIG. 1.

FIG. 7 is a front elevation view of the headset for helmet illustrated in FIG. 1.

FIG. 8 is a rear elevation view of the headset for helmet illustrated in FIG. 1.

FIG. 9 is a top plan view of the headset for helmet as illustrated in FIG. 1; and,

FIG. 10 is a bottom plan view of the headset for helmet illustrated in FIG. 1.

The broken lines depict elements of headset for helmet that form no part of the claimed design.

1 Claim, 10 Drawing Sheets
